UNITED STATES PATENT OFFICE.

WALTER WILLIAMSON, OF EVERETT, MASSACHUSETTS.

SPEEDOMETER.

Application filed June 4, 1918. Serial No. 238,103.

This invention relates to speedometers and its object is to secure a speedometer of a high degree of accuracy and of simple construction and one that is adapted to scientific purposes, where exact measurements of speed are required.

It is illustrated by the accompanying drawings in which:

Fig. 1 is a plan view showing the dial;
10 Fig. 2 is a plan view with the dial removed;

Fig. 3 is a sectional view on line 3—3
Fig. 2;

15 Fig. 4 is a sectional view on line 4—4
Fig. 2;

Fig. 5 is an enlarged sectional view on
line 5—5 Fig. 2;

20 Fig. 6 is a sectional view on line 6—6
Fig. 5;

Fig. 7 is a sectional view on line 7—7
Fig. 5;

The several parts of the device are mounted on frame 1, through which extends main driving shaft 2 carrying on its inner end

25 bevel gear 3 which engages bevel gear 4 on sleeve 5 journalled in the frame and furnished interiorly with a series of ball and socket bearings 6 which engage spiral groove 7 on speed disc shaft 8 slidingly and rotatively disposed in sleeve 5 and having a bearing 9 in the frame; which arrangement provides for a limited lengthwise movement of speed disc shaft 8 in sleeve 5.

This speed disc shaft is furnished near 35 its outer end with speed disc 10 rigidly affixed thereto, which speed disc rests on time disc 11 at right angles thereto, said time disc 11 being rigidly affixed to arbor 12 of the clock mechanism, which arbor is furnished with spring 13 adapted to hold 40 the discs in frictional contact.

The outer end of speed disc shaft 8 contacts with the arm 14 mounted on the upper end of shaft 15 journalled in the frame and carrying at its lower end sector 16 which engages spring controlled pinion 17 on the lower end of shaft 18 journalled in the frame and carrying on its upper end hand 19 adapted to indicate speeds on dial 20.

50 The arrangement of the various parts is such that normally (when main shaft 2 is not rotating) speed disc 10 contacts with the center of time disc 11 and thus positioned is not affected by the rotation of the time

disc and consequently the hand points to 55 0 on the dial.

It may be here noted that, when the time disc is rotating, its center is of course stationary, while the speed of any other point on the disc is proportionate to its distance 60 from the center being greater as such distance increases.

When the main shaft 2 begins to rotate, it rotates sleeve 5, while speed disc 10 by its spring-controlled frictional engagement 65 with the center of time disc 11 prevents speed disc shaft 8 from freely rotating with the sleeve, and speed disc shaft 8 in consequence is driven outwardly by means of the ball and socket bearings 6 traveling in 70 spiral groove 7, thereby carrying the speed disc out from the center of the time disc to a point which travels at a speed equal to that of the sleeve, when the two discs travel synchronously at a speed indicated on the 75 dial; and, as the speed of the main shaft increases or decreases, the point of contact between the discs travels away from or towards the center of the time disc; and, when the main shaft ceases to rotate, the 80 point of contact between the discs is again the center of the time disc; and the spring controlled pinion 17 returns the hand 19 to 0 on the dial and through sector 16 maintains the engagement of arm 14 with the 85 outer end of shaft 8 through all its movements.

Another feature of the invention is the employment of the main shaft 2 to wind the clock and keep it wound during the rotation of said shaft; for which purpose the shaft is furnished with fixed collar 21 which carries lug 22 adapted, when the shaft rotates, to engage lug 23 carried by pawl 24 pivoted at 25 to the side of the hollow 90 ratchet wheel 26 and held against said ratchet wheel by spring 27; said wheel being rotatably mounted on main shaft 2 and controlled by spring pressed pawl 28 mounted on the frame; the pawl 24 being 100 furnished with lug 29, which extends through slot 30 in the ratchet wheel; to which lug 29 is fixed the outer end of the clock spring 31 disposed in said hollow ratchet wheel and having its inner end attached to hub 32 of clock gear 33 rotatably mounted on shaft 2 and engaging pinion 12^a affixed to time disc arbor 12.

2

By this arrangement shaft 2 rotates ratchet wheel 26 thereby winding clock spring 31 until said spring in the process of winding draws lug 29 inwardly until lug 23 slips past lug 22, the clock spring then being wound; and as said spring unwinds it carries lug 29 outwardly and lug 23 is again engaged by lug 22 and thereby renews the winding process and prevents the clock from running down so long as shaft 2 rotates; and when shaft 2 ceases to rotate the clock gradually runs down and remains in that condition until again wound up as explained.

15 Still another feature of the invention is the employment of shaft 2 to perform the further function of operating the counter shafts 34 and 35 and this is accomplished by furnishing the sleeve 5 with the gear 36 which engages pinions 37 and 38 engaging respectively the gears 39 and 40 affixed respectively to said counter shafts 34 and 35 carrying respectively the counter discs 41 and 42.

25 I claim:

1. In a device of the class described, the combination of a driving element adapted to be driven by a mechanism the speed of which is to be indicated, a driven element, mechanism operated by said driving element for actuating said driven element, said mechanism including a spring; means operable by said spring whereby said spring may be wound by said driving element, clock mechanism for controlling the speed of said driven element, independent means operatively connected with said driving element and with said driven element and arranged to change its position as the relative speeds of said driving and driven ele-

ments vary, and indicating mechanism connected with and operated by said independent means.

2. In a device for indicating the speed of a mechanism, a movable element adapted to be driven at a speed proportional to the speed of said mechanism, a second movable element, means for actuating said second named element including a spring; means operable by said spring whereby said spring may be wound by said first movable element, means comprising a clock mechanism for controlling the speed of said second-named element, means operatively connecting said elements to effect relative movement thereof upon change in their relative speeds, and indicating means actuated by the relative movement of said elements.

3. In a device for indicating the speed of a mechanism, a disc, a second disc having the lateral surface thereof contacting with the periphery of said first-named disc, means for actuating said second-named disc including a spring, means comprising a clock mechanism for controlling the operation of said second-named disc, a screw-threaded spindle engaging said first-named disc and driven at a speed proportional to the speed of said mechanism, means to drive said spindle; means operable by said spring whereby said spring may be wound by said spindle driving means; and indicating means actuated by the relative movements of said discs upon change in the relative speeds of said first-named disc and said spindle.

In testimony whereof I have affixed my signature.

WALTER WILLIAMSON.
